UNITED STATES PATENT OFFICE.

HENRY EDWARDS KING, OF BUNKIE, LOUISIANA.

AUTOMATIC LIGHT-SWITCH.

No. 868,870.

Specification of Letters Patent.

Patented Oct. 22, 1907.

Application filed February 23, 1907. Serial No. 358,839.

To all whom it may concern:

Be it known that I, HENRY EDWARDS KING, a citizen of the United States, residing at Bunkie, in the parish of Avoyelles and State of Louisiana, have invented a new and useful Automatic Light-Switch, of which the following is a specification.

This invention relates to automatic alarms and more particularly to an electric switch especially designed for use in connection with an alarm clock for automatically closing a lighting circuit at pre-determined intervals.

The object of the invention is to provide a switch including a pair of contact members one of which is arranged in the path of movement of the hammer of an alarm clock or similar device so that when the alarm is sounded the hammer will move the adjacent contact to circuit closing position and thus light the lamps.

A still further object of the invention is to generally improve this class of devices so as to increase their utility, durability and efficiency.

With these and other objects in view the invention consists in the construction and novel combination and arrangement of parts hereinafter fully described, and illustrated in the accompanying drawings, it being understood that various changes in form, proportions and minor details of construction may be resorted to within the scope of the appended claims.

In the accompanying drawings forming a part of this specification: Figure 1 is a front elevation of an electric switch constructed in accordance with my invention showing the movable contact in position to be engaged by the hammer of an alarm clock. Fig. 2 is a rear elevation of the casing or housing showing the relative position of the contact members. Fig. 3 is a longitudinal sectional view taken on the line 3-3 of Fig. 2. Fig. 4 is a transverse sectional view taken on the line 4-4 of Fig. 2.

Similar numerals of reference indicate corresponding parts in all of the figures of the drawings.

The device comprises a casing or housing 5 designed for attachment to a wall or other suitable support and provided with vertically disposed lugs 6 having perforations formed therein for the reception of screws or similar fastening devices 7 whereby the casing may be conveniently supported on the wall.

The casing 5 is provided with a pivoted cover or closure 8 having a spring catch or similar fastening device 9 secured thereto and adapted to engage the top of the casing for locking the cover in closed position.

The opposite end walls of the casing are provided with aligned openings in which are seated bearing collars or sleeves 10 adapted to receive a pair of contact members 11 and 12, there being bushings 13 formed of rubber, vulcanized fiber or other suitable insulating material interposed between the sleeves 10 and the walls of the adjacent opening, as shown.

The contact members 11 and 12 are connected to the terminals of a lighting circuit 14 including a battery 15 and one or more incandescent lamps 16. The contact member 11 is relatively stationary while the member 12 is mounted for longitudinal movement within the casing or housing and is provided with a terminal head 17 which extends in the path of movement of the vibrating hammer 18 of an ordinary alarm clock, indicated at 19.

The head 17 is eccentrically mounted on the adjacent end of the movable contact 12 and is preferably provided with a disk 20 formed of rubber or other suitable yieldable material adapted to receive the impact of the hammer 18.

Secured to the inner wall of the cover or closure 8 is a strip of metal 21 having a laterally extending flange 22 defining a pocket for the reception of an insulating block 23, the latter being preferably formed of glass or other suitable material and having a convex face 24 adapted to bear against the curved or deflected end 25 of the stationary contact member 11.

The free or inner end of the movable contact member 12 is provided with a laterally extending lip 26 adapted to engage the deflected end 25 of the stationary member 11 and thereby close the lighting circuit when the contact 12 is moved longitudinally by engagement with the hammer 18 of the alarm clock.

In operation the clock is set to sound the alarm at any pre-determined period and the movable contact 12 arranged in the path of movement of the hammer 18, as best shown in Fig. 1 of the drawing. When the alarm is sounded the hammer 18 will strike the head 17 of the movable contact and force the latter longitudinally in engagement with the flattened end of the stationary contact 11 thus automatically closing the circuit and lighting the lamp or lamps. In order to extinguish the lamps it is merely necessary to exert a longitudinal pull on the head or finger piece 17 when the contacts will be separated and the lighting circuit broken.

Attention is called to the fact that by having the insulating block 23 formed with a convex face and the flattened end of the stationary contact 11 bent to conform to the contour of the face of the block, the contact 12 when moved to circuit closing position will make a wipe contact with the member 11 and thus insure a good electrical connection between the two. It will also be observed that when the deflected end of the movable contact 12 engages the inclined end 25 of the stationary contact the end 26 of the movable contact will be forced outwardly thus exerting a spring action on the stationary contact and serving as an additional means for holding both contacts in circuit closing position. By having the insulating block 23 arranged within the pocket and the latter secured to the pivoted wall or closure 8 when said block becomes broken or otherwise injured from rough usage or from any other cause the same may be

readily detached by moving the door or closure 8 to open position and removing the block through the open end of the pocket, as will be readily understood.

From the foregoing description it is thought that the 5 construction and operation of the device will be readily understood by those skilled in the art and further description thereof is deemed unnecessary.

Having thus described the invention what is claimed is:

- 10 1. An electrical switch including co-acting contacts one of which is provided with a terminal head having a cushioning member secured thereto, an energized circuit the terminals of which are secured to the contacts, an insulating block bearing against and forming a support for the 15 adjacent end of one of the contacts, and an alarm clock having a vibrating hammer adapted to engage a head of the adjacent contact for moving the latter to circuit closing position.
- 20 2. An electrical switch including a casing, relatively stationary and movable contacts extending through the walls of the casing, one of said contacts being provided with a terminal head, an insulating block disposed within the casing and engaging one of said contacts, an energized circuit connected with the contacts, and an alarm clock 25 the hammer of which is adapted to engage the head of the adjacent contact for moving the latter to circuit closing position.
- 30 3. An electrical switch including a casing having a pivoted closure, relatively stationary and movable contacts extending through the walls of the casing, an insulating block secured to the closure and bearing against the stationary contact, an energized circuit connected with the contacts, and an alarm clock having a vibrating hammer 35 adapted to engage the movable contact for moving the same to circuit closing position.
- 40 4. An electrical switch including a casing, relatively stationary and movable contacts extending through the walls of the casing, one of said contacts being provided with a curved terminal and the adjacent contact with a laterally 45 extending lip, an insulating block having a convex face adapted to bear against the curved terminal of the stationary contact, a head secured to the movable contact, an energized circuit, the terminals of which are connected with said contacts, and an alarm clock having a vibrating hammer adapted to engage the head for moving the adjacent contact to circuit closing position.
- 50 5. An electrical switch including a casing, relatively stationary and movable contacts extending through the walls of the casing, an insulating block bearing against the stationary contact, a head eccentrically mounted on the end of the movable contact, an energized circuit the terminals of which are connected with said contacts, and an 55 alarm clock having a vibrating hammer adapted to engage the head for moving the latter to circuit closing position.
- 60 6. An electrical switch including a casing, relatively stationary and movable contacts extending through the walls of the casing, a pocket arranged within the casing, a removable insulating block seated within the pocket and having a convex face adapted to bear against the stationary contact, an energized circuit connected with the contacts, and an alarm including a vibrating hammer adapted to engage the movable contact for actuating the latter to 65 close the circuit.
- 70 7. An electrical switch including a casing having a pivoted closure, a metal strip secured to the closure and provided with a laterally extending flange forming a pocket, relatively stationary and movable contacts extending through the walls of the casing, an insulating block seated in the pocket and having a convex face adapted to bear against the stationary contact, an energized circuit connected with the contacts, and an alarm including a vibrating hammer adapted to engage the movable contact for actuating the latter to close the circuit.
- 75 8. An electrical switch including a casing provided with a pivoted closure and having its end walls formed with aligned openings, bearing sleeves seated in said openings, insulating bushings interposed between the sleeves and the walls of the openings, an insulating block secured to the pivoted closure and having a convex face, relatively stationary and movable contacts extending through the sleeves, one of said contacts being bent to conform to the convex face of the insulating block and the adjacent contact being provided with a laterally extending lip adapted to engage the curved end of the stationary contact, an energized circuit connected with the contacts, and an 80 alarm including a vibrating hammer adapted to engage the movable contact for actuating the latter to close the circuit.
- 85 9. An electrical switch including a casing having a pivoted closure, a pocket secured to the closure, an insulating block seated in the pocket and having a convex face, relatively stationary and movable contacts extending through the walls of the casing, one of said contacts being bent to conform to the convex face of the insulating block and the adjacent contact being provided with a laterally extending lip adapted to engage the stationary contact, an enlarged head secured to one end of the movable contact, an energized circuit connected with the contacts, and an alarm 90 including a vibrating hammer adapted to engage the movable contact for actuating the latter to close the circuit.
- 100 10. In testimony that I claim the foregoing as my own, I have hereto affixed my signature in the presence of two witnesses.

HENRY EDWARDS KING.
